(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a front view thereof;

FIG. 4 is an opposite side view thereof;

FIG. 5 is an opposite side front perspective view thereof; and,

FIG. 6 is a top view thereof.

The broken lines immediately adjacent to the shaded areas define the bounds of the claimed design and form no part thereof. The contrast in shading represents a contrast in appearance only. The six unshaded racetrack-shaped area demarcated by broken lines represent features that form no part of the claimed design. The broken lines depicting the remainder of the shoe show features that form no part of the claimed design.
